UNITED STATES PATENT OFFICE

SIGMUND FISCHER, OF PROVIDENCE, RHODE ISLAND; SIGMUND W. FISCHER, JR., ADMINISTRATOR OF SAID SIGMUND FISCHER, DECEASED, ASSIGNOR TO ALMA M. FISCHER, OF PROVIDENCE, RHODE ISLAND

SHOE STRAP

Application filed July 20, 1928. Serial No. 294,271.

My invention relates to shoe straps, particularly those adapted to form a cross strap over the instep of the wearer detachably attachable to the opposite side margins of a low shoe, pump or slipper both for ornamental purposes and to bind said shoe to said foot.

An object of my invention is to provide a strap of this description with an end clip or an end clamping means to engage the side margins of the shoe and to become permanently attached thereto without any rubbing on the patent-leather or other shoe surface, which end clip or clamping means is pivotally attached to the strap itself to permit the strap to swing relative to the margins of the shoe for ease on the wearer in use.

A further object of my invention is to provide a shoe strap of ornamental appearance preferably including metal ornamentation extending over the instep. It is found in use that these metallic ornaments often wear the instep and tear the stocking. An object of my invention therefore is to provide a strap having a protective covering underneath the metallic ornaments to protect both the instep and the stocking therefrom.

Further features of my invention relate to the specific structure of strap I preferably employ which consists preferably of an inelastic metallic portion and an elastic fabric portion at each end thereof. The pressure is usually exerted on the center of the instep and if the portion over the instep is made expansible it will result in a pulling and stretching in use of the metallic ornaments over this portion of the instep. I preferably so construct the strap itself that the portion which extends over the center of the instep and actually bears the weight of supporting the shoe is inelastic and I provide elastic portions adjacent each end of the strap where there is no downward pressure on the strap or pressure of any description against the stocking or side of the instep due to the normal contour of the foot.

These and such other objects of my invention as may hereinafter appear will be best understood from a description of the accom-

panying drawings, which illustrate various embodiments thereof.

In the drawings, Fig. 1 is a perspective view of the preferred embodiment of my strap in attached position on a shoe.

Fig. 2 is a rear elevation of my improved strap in detached position.

Fig. 3 is a diagrammatic perspective view taken from the inside of the shoe showing the type of end clip I preferably employ and the pivotal attachment of the end of the strap thereto to permit its swinging movement in use.

Fig. 4 is an enlarged sectional view taken along the line 4—4 of Fig. 2.

Fig. 5 is a reverse plan view of an end of a modified form of my invention.

Fig. 6 is a side elevation of an end of the modified form of my invention shown in Fig. 5.

In the drawings, wherein like characters of reference indicate like parts throughout, 10 generally indicates a shoe strap constructed in accordance with the teachings of my invention. Said strap includes the strap proper 12 and means 14, such as the end clips 14 shown on each end thereof to detachably clamp each end thereof to opposite shoe margins, preferably as shown pivotally connected to each end of said strap and adapted to be detachably immovably secured to each opposite shoe margin 16 of the shoe 18 as shown in Fig. 1.

I employ the word shoe broadly to include any suitable type of shoe, though, it is obvious that my invention is particularly adapted to retain a low shoe, slipper, or pump to the foot.

My invention is preferably employed with the strap portion 12 ornamented in any desired manner, preferably by means of the ornaments 20 attached together in end to end relationship. As stated, these metallic ornaments 20 have a rough hard surface and often have sharp protruding portions which not only tend to wear the center portion of the instep but also in use tend to tear holes in the stocking. I therefore preferably provide means located underneath the sharp protruding portions of the strap and connected

to said strap to protect the instep from said sharp protruding portions and in the embodiments of my invention shown, said means comprises the inelastic protective fabric 22 also extending over the instep underneath said metallic portions and connected to said strap 12. Said inelastic fabric 22 may consist of textile fabric, leather or other suitable material. In the preferred embodiment of my invention shown in Figs. 1-4 the ornaments 20 are provided with transverse slits 24 near each end thereof and the inelastic fabric strip 22 is threaded through the transverse slits 24 in each metallic ornament 20 and thus underneath each respective ornament 20, the ornaments 20 thus being threaded in end to end relationship on the inelastic fabric portion 22 forming the metallic strap 12. In the embodiment of my invention shown in Figs. 5 and 6 the metallic strap is preferably formed by having the ornaments 20 linked or otherwise joined together as at 26 in end to end relationship and with the inelastic fabric portion 22 attached to the ends of the strap 12 formed by the connected ornaments 20 and extending over the instep and underneath said metallic strap 12 having the sharp protruding portions.

30 While for certain features of my invention the entire strap 12 may consist of an inelastic portion it is desirable in use that the strap be elastic or extensible so as to give slightly in the normal movements of the shoe 35 in use. So far as I am aware others have hitherto attempted to construct the entire strap of extensible metallic pieces or otherwise elastic, thus where metallic ornaments are employed to cause them to move relative- 40 ly back and forth over the stocking and center portion of the instep tending to wear the instep and tear the stocking. In order to make my improved strap 12 extensible, I preferably provide it with the elastic portions 28 45 adjacent each end thereof and attached in any suitable manner to the ends of the inelastic strap portion 22. While the inelastic portion 22 may be joined to the elastic portions 28 in any suitable manner I preferably 50 join it thereto by the metallic clamps 30. It is thus obvious that as the elastic portions 28 are located adjacent each strap end that a stretching movement is permitted at a place where the portion of the strap itself is in 55 a substantially vertical plane and where there will be substantially no rubbing against the side of the instep or stocking.

As stated hitherto, I preferably provide means to detachably clamp each end of said 60 strap 10 to opposite shoe margins. In the preferred embodiment shown, I preferably provide clamping means 14 detachably immovably securable to said opposite shoe margins and in order to permit the normal movement of the strap 12 in use relative to the side

70 margins of the shoe, I preferably pivotably connect each end of the strap 12 to said clamping means. As stated it is desirable to immovably clamp the clamping means to each opposite shoe margin in order to prevent movement of a single pivot point thereover to cause a wear on the patent-leather or other leather employed or wear on the inner lining of the shoe. It is also desirable to 75 wedgedly clamp the ends of the strap 10 to said opposite shoe margins 16 in a manner such that in use the ends of the strap will not become readily disengaged therefrom. While any suitable type of clamping means may be employed for this purpose, I preferably provide end clips 14 for this purpose which in my preferred embodiment comprise a pair of clamping jaws 32 and 34 respectively attached to each end of said strap and pivotably connected to each end of said strap, 80 in my preferred embodiment shown comprising the top plate or jaw 32 and clamping lever or jaw 34. In order to immovably attach the end clips 14 to the shoe margin 16 I preferably provide a plurality of spurs 36 85 located on one of each pair of jaws 32 and 34 to immovably engage the shoe without rubbing the shoe surface. While any suitable type of end clip may be employed. I 90 preferably employ a modified type of end clip of the type shown in my patent application for strap ends and strap end clips Serial No. 235,255, filed Nov. 23, 1927, which consists of a modified collar button modified to form a wedge to resist a lateral pull thereon as is present in the type of shoe strap shown in this application by the upward pressure exerted by the instep of the wearer. My preferred type of end clip therefore consists of the top plate 32 having the clamping 100 lever 34 resiliently mounted thereon in the diaphragm plate 38 and as shown in said application the end of each spur 36 is preferably flattened as at 40 (see Fig. 4) and the dia- 105 phragm 38 is provided with the downwardly projecting wedge lip 42 to enable the spurs 36 and lip 42 to form wedge means to resist a lateral pull on the end clip 14. In my preferred embodiment as shown in Fig. 3, I 110 preferably employ a pair of spurs 36 adapted to straddle the wedge lip 42.

115 While any suitable type of means may be employed to pivotably attach the end clips or clamping means 14 to the ends of the strap 12, I preferably employ the metallic clamps 44 surrounding the outer ends of the elastic portions 28 and having the hooks 46 projecting outwardly therefrom adapted to be pivotably secured through the holes 48 in 120 the top plates 32.

125 Though I preferably detachably secure each end of my improved strap 10 to opposite shoe margins, it is obvious that one end may be permanently affixed thereto and 130

the other end detachably securable thereto in the manner hitherto described.

It is understood that my invention is not limited to the specific embodiments shown 5 and that various deviations may be made therefrom without departing from the spirit and scope of the appended claims.

What I claim is:

1. A detachable shoe strap, comprising a 10 strap of a length to extend over the instep of the wearer and substantially to opposite margins of the shoe consisting of an elastic portion near each end thereof, metallic in- 15 elastic ornament elements arranged over the instep and an inelastic protective fabric extending over the instep underneath said metallic elements and connected to said metallic elements and to said elastic portions, and means to detachably clamp each end of said 20 strap to opposite shoe margins.

2. A detachable shoe strap, comprising a 25 strap of a length to extend over the instep of the wearer and substantially to opposite margins of the shoe, consisting of an elastic portion near each end thereof, an inelastic fabric portion extending over the instep and connected to said elastic portions, metallic 30 ornaments strung on said inelastic portion, and means to detachably clamp each end of said strap to opposite shoe margins.

3. A detachable shoe strap, comprising a 35 strap of a length to extend over the instep of the wearer and substantially to opposite margins of the shoe, consisting of an elastic portion near each end thereof, metallic ornaments having transverse slits near each end thereof, an inelastic fabric portion extending over the instep, through said ornament slits and underneath each respective ornament 40 and connected to said elastic portions, and means to detachably clamp each end of said strap to opposite shoe margins.

In testimony whereof I affix my signature.
45 SIGMUND FISCHER.
